The ornamental design for a strap tab for a strap, as shown and described.(21) Appl. No.: **29/441,053****DESCRIPTION**(22) Filed: **Dec. 31, 2012**

FIG. 1 is a perspective view showing a first surface of a strap tab for a strap on an end of a strap in an engaged configuration, showing my design.

(51) **LOC (10) Cl.** **24-01**

FIG. 2 is a perspective view showing a second surface of the strap tab for a strap of FIG. 1 on an end of a strap in an engaged configuration.

(52) **U.S. Cl.**

FIG. 3 is a perspective view showing the first surface of the strap tab for a strap of FIG. 1 in a closed configuration.

(53) **USPC** **D24/190**

FIG. 4 is a plan view showing the first surface of the strap tab for a strap of FIG. 3.

(58) **Field of Classification Search**

FIG. 5 is a plan view showing the second surface of the strap tab for a strap of FIG. 3.

CPC A41F 11/02; A44B 18/0061; A44B 18/0084;
A61F 15/006; A61F 13/5622; A61F 13/62
USPC D24/189-193; 24/306, 442; 602/4-6,
602/20, 27, 61-62, 79; 128/865-866, 878,
128/876; 604/20, 21

FIG. 6 is a first side elevational view of the strap tab for a strap of FIG. 3.

See application file for complete search history.

FIG. 7 is a second side elevational view of the strap tab for a strap of FIG. 3.

(56) **References Cited**

FIG. 8 is a bottom elevational view of the strap tab for a strap of FIG. 3.

U.S. PATENT DOCUMENTS

FIG. 9 is a top elevational view of the strap tab for a strap of FIG. 3; and,
